HAIR WAVING DEVICE

Walter H. Hermsdorf, Chicago, Ill., assignor to
 Chain Store Products Corporation, Chicago,
 Ill., a corporation of Delaware

Application April 16, 1936, Serial No. 74,660

5 Claims. (Cl. 132—31)

This invention relates to hair waving devices of the type comprising a pair of spring-pressed pivotally connected elongated hair-gripping members adapted for engaging and retaining a mass of hair therebetween for forming a wave in the hair. More particularly the present invention is directed to devices of the above character wherein the bottom edges of the gripping members are provided with teeth for assisting in combining and gathering a mass of hair between said gripping members.

Devices of this type generally are applied to the hair when it is moist and are permitted to remain in place thereon until the hair assumes and retains the wave formed by the pressure of the gripping members.

Heretofore devices of this type have been constructed so that the inner surfaces of the gripping members are relatively flat and substantially parallel to each other in closed position. Manifestly, such arrangement tends to exert even pressure on all portions of the hair comprising the wave, and often, if a large mass of hair is gathered between the gripping members there is a tendency during closing movement of said members to squeeze or force some of the mass of hair downwardly and out from between the gripping members.

One of the objects of this invention is to provide an improved form of device of the above mentioned character which is constructed and arranged to facilitate gathering and retaining a mass of hair between the gripping members.

Another object resides in forming the gripping members in a manner for exerting greatest pressure on the mass of hair adjacent the bottom of the wave, that is, the portion immediately adjacent the scalp, for effectively retaining the hair in wave formation after the device is removed.

A further object of my invention is to provide an improved device of the character indicated which is simple in construction and economical to manufacture.

Other objects and advantages will appear in the following description taken in connection with the accompanying drawing in which:

Fig. 1 is a side elevation of the hair waving device, embodying the present invention.

Fig. 2 is a top view of the device.

Fig. 3 is a section through the device, taken as indicated at line 3—3 on Fig. 1.

Fig. 4 is a section similar to Fig. 3, showing the device disposed in operative position on a mass of hair.

Referring now in detail to the drawing: The

device embodying this invention includes a pair of elongated hair-gripping members 10 and 11, preferably formed as sheet metal stampings, and said members are formed with integral angularly disposed finger gripping portions, 12 and 13 respectively. Said portions 12 and 13 are each provided with a pair of ears 14 and 15, respectively, disposed in overlapping relation, pivotally connected together by a pin 16, as seen in Fig. 2. Said gripping members are yieldingly urged toward each other by a coil spring 18, surrounding said pin 16, and having its end portions engaging the respective finger portions 12 and 13, as may be seen in Fig. 2.

The bottom edges of said members 10 and 11 are of arcuate formation, as seen in the drawing, to conform to the contour of the head of the user of the device, and the body of said gripping members is so formed that the inner surfaces thereof contact each other immediately adjacent said bottom edges of the members. As may be seen in the drawing, the inner surfaces of said members are bulged or extend outwardly, as indicated at 10a and 11a, respectively, immediately above said contact area, and extend substantially throughout the length of said members. This construction permits accommodating a substantial mass of hair between said members, and the pressure exerted by said members on the mass of hair is greatest at the bottom of the wave, in line with said contact portion of the members, and thus there is no tendency to force the hair out from between said gripping members. The wave thus formed will be relatively permanent and the mass of hair looped between the gripping members will be permitted to assume a more natural form. To facilitate setting of the hair in wave formation said members are each provided with a series of longitudinally spaced apart apertures, 20, to assist in circulating air through the moist mass of hair for evaporating the moisture, and causing said hair to acquire a definite set wave formation.

The bottom edges of the members 10 and 11 are provided with teeth 21, formed as an integral part of said members and conform to the arcuate contour of said bottom edges. Said teeth extend obliquely downwardly toward the opposite member, and the teeth of one of said members are disposed in offset relation to the teeth of the other so that said teeth intermesh in the closed position of the gripping members as seen in Fig. 3.

When the device is used, the finger grip portions 12 and 13 are compressed, opening the lower edge of the gripping members 10 and 11, against

the reaction of the spring 18, and as the teeth are brought into contact with the hair the pressure is released on said finger grip portions, permitting the teeth to gather a mass of hair and force it upwardly between the gripping members 10 and 11, as seen in Fig. 4. When the pressure on the finger grip portions is entirely released, the moist hair becomes compressed between the inner surfaces of the members 10 and 11, to form a wave and the greatest pressure, (due to the outward bulging of said members) is exerted by the lower inner edge of the gripping members, adjacent the bottom of the wave, which effectively sets and maintains the hair in wave formation.

15 Although I have shown a preferred embodiment of my invention, manifestly, it is capable of modification and rearrangement without departing from the spirit and scope thereof. I do not, therefore, wish to be understood as limiting 20 my invention to the specific form and application above indicated, except as so limited in the appended claims.

I claim as my invention:

1. In a device of the character described, a 25 pair of elongated spring-pressed pivotally connected hair-gripping members, the bottom edges of said members being provided with teeth, the inner surfaces of members, adjacent said bottom edges, contacting each other in the closed position of said members, the inner surface of one member, immediately above said contact area, extending outwardly substantially throughout the length of the member to provide a longitudinal space for the reception of the folded or bent 30 portion of the hair gripped between said members.
2. In a device of the character described, a pair of elongated spring-pressed pivotally connected hair-gripping members, the bottom edges of said members being provided with teeth, the inner surfaces of members, adjacent said bottom edges, contacting each other in the closed position of said members, the inner surfaces of said members, immediately above said contact area, extending outwardly substantially throughout the 35 length of said members to provide a longitudinal space for the reception of the folded or bent portion of the hair gripped between said members.
3. In a device of the character described, a pair of elongated spring-pressed pivotally con-

nected hair-gripping members, the bottom edges of said members being provided with teeth, the inner surfaces of members, adjacent said bottom edges, contacting each other in the closed position of said members, the inner surfaces of said members, immediately above said contact area, extending outwardly substantially throughout the length of said members to provide a longitudinal space for the reception of the folded or bent portion of the hair gripped between said members, 10 said members each being provided with a series of longitudinally spaced apart apertures above said contact area.

4. In a device of the character described, a pair of elongated spring-pressed pivotally connected hair-gripping members, the bottom edges of which are of arcuate formation, said arcuate edges each being provided with teeth for accumulating a quantity of hair for retention in wave form between said members, the inner surfaces 20 of said members, adjacent said edges, contacting each other in the closed position of said members when not acting in hair gripping capacity, each of said members being bulged outwardly, above said contact area, substantially throughout the 25 length thereof to provide a space for the folded or bent portion of the hair gripped between said members.

5. In a device of the character described, a pair of elongated spring-pressed pivotally connected hair-gripping members, the bottom edges of which are of arcuate formation to conform with the curvature of the head, said arcuate edges each being provided with teeth to accumulate a quantity of hair for retention in wave form between said members, the inner surfaces of said members adjacent said edges normally contacting each other in the closed position of said members when the same are not acting in hair gripping capacity, each of said members being bulged outwardly above said contact area substantially throughout the length thereof to provide a space for the folded or bent portion of the hair wave, the primary gripping action of said members upon the hair when in hair gripping 40 capacity taking place at that area of the members which is in contact during normal position of said members.

WALTER H. HERMSDORF.
